UNITED STATES PATENT OFFICE.

JOSEPH BENZION, OF CHICAGO, ILLINOIS.

SHADE-SUPPORT.

SPECIFICATION forming part of Letters Patent No. 622,837, dated April 11, 1899.

Application filed June 24, 1898. Serial No. 684,384. (No model.)

To all whom it may concern:

Be it known that I, JOSEPH BENZION, a citizen of the United States, residing at Chicago, in the county of Cook and State of Illinois, 5 have invented a new and useful Improvement in Shade-Supports, of which the following is a specification.

My invention relates to an improvement in shade-supports for use more especially in 10 connection with combined globes and chimneys which present shoulders upon which the shades rest.

My object is to provide permanent spacing pieces of refractory material, such as asbestos, 15 attached to the chimney or shade and operating to keep them apart, whereby air will pass freely between them and tend to cushion and prevent heating of the shade.

In the drawings, Figure 1 is a vertical section, 20 on line 1 of Fig. 2, of a chimney and shade, illustrating my improvements in their preferred form, the spacing-pieces being attached to the chimney; Fig. 2, a top plan view of the chimney with the shade removed; Fig. 25 3, a view similar to Fig. 2, but showing a modification; and Fig. 4, a broken vertical section of the modified structure shown in Fig. 3.

A is a lamp globe or chimney having the expanded or globe portion A', contracted chimney portion A², and annular shoulder A³.

B is a shade provided with an opening s, somewhat larger than the chimney A², surrounded at the under side by a shoulder s'. Cemented upon or otherwise permanently attached to the outer surface of the shoulder portion A³ are spacing-pieces t, of asbestos or equivalent refractory material which will not be destroyed by the heat of the flame.

In the preferred construction the spacing pieces are looped or scalloped, as shown in Fig. 2, to form attaching ends t' and intermediate raised portions t², whereby an air-passage t³ is provided between the attaching ends beneath the intermediate portion. The 45 pieces are secured in place preferably by cementing them at the ends t' to the surface of the shoulder A³.

In practice three or more spacing-pieces are provided and placed approximately equidistant apart around the shoulder to form a suitable support for the shade, which rests at its

shoulder s' upon the spacing-pieces. Asbestos, which is the material I prefer to employ, is sufficiently soft to cushion the shade and prevent its rattling upon the support when 55 jarred. The cement used for securing the spacing-pieces in place should obviously be of a character which will not be affected by the heat of the flame. The area of contact of the spacing-pieces with the chimney is so 60 small that the rush of air through the passages t³ and across the outer surfaces of the pieces will tend to keep them cool, prevent their being deleteriously affected by the heat, and also tend to prevent the conduction and 65 radiation of heat from the chimney to the shade. The shade rests upon the raised parts of the spacing-pieces only, whereby the area of contact between them is very small, which prevents conduction of heat to any great extent 70 from the chimney to the shade by the spacing-piece material.

In the modified construction the spacing-pieces t are short flat pieces of asbestos or the like cemented or otherwise firmly secured in 75 place. They are unprovided with the raised parts t², and the intermediate air-passages t³ are not present.

The gist of my invention lies in providing spacing-pieces of refractory material permanently attached to the chimney or shade at intervals around the chimney to afford a free passage of air between the chimney and shade, and thus prevent undue heating of the latter, and while I prefer to construct my improvements as shown and described they may be modified in the matter of details without departing from the spirit of my invention as defined by the claims.

What I claim as new, and desire to secure 90 by Letters Patent, is—

1. The combination with a globe or chimney formed near its top with an annular shoulder, and shade having an opening surrounded by an annular shoulder to be supported by the 95 shoulder on the chimney, of a series of independent spacing-pieces of refractory material cemented to one of said shoulders to engage the other said shoulder, substantially as and for the purpose set forth.

2. The combination with a globe or chimney formed near its top with an annular shoulder,

and shade having an opening surrounded by an annular shoulder to be supported by the shoulder on the chimney, of a series of independent spacing-pieces of refractory material having attaching surface portions at which they are cemented to one of said shoulders, and intervening portions raised to form air-

passages beneath them, and engage the other said shoulder, substantially as and for the purpose set forth.

JOSEPH BENZION.

In presence of—

M. J. FROST,
R. T. SPENCER.
